HAND GUARD

Peter Jerome Diffley, Springfield, Mass.

Application June 12, 1942, Serial No. 446,708

1 Claim. (Cl. 42—75)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to a firearm and particularly an improved handguard therefor.

On modern military rifles, particularly of the type similar to U. S. rifle, caliber .30, M1, the fore-end of the stock is anchored to the barrel by means of a metallic band which surrounds the barrel and has an extension below the barrel to securely grip the appropriately shaped fore-end of the stock. Such metallic band is generally referred to as the lower band. In prior designs of this rifle this lower band necessitated a two-piece wood handguard, one piece extending from the chamber end of the barrel to the lower band and the second piece extending from the lower band for a suitable protective distance along the barrel. The cross-section of both of these handguard members was reduced at the ends adjacent the lower band so as to fit into slots in the lower band for securing purposes. To insure that these dovetailed ends would stay in position, it was necessary that each of the two handguard members be secured to the barrel in such manner as to prevent any excessive longitudinal movement of either of the handguards with respect to the barrel. This was accomplished by the snug fitting of the rear handguard between the receiver shoulder and the lower band, and the front handguard between the gas cylinder assemblage and the lower band.

The resulting rigid construction can cause much difficulty in the nature of warping of the barrel. Such warping might be caused, for example, by the greater heat expansion of portions of the barrel than that of the wooden handguard which is secured thereto. Barrel strain also occurs in the assembly on the barrel of a slightly oversized gas cylinder assemblage, one end of which abuts against the end of the handguard assembly. This two-piece handguard arrangement further permitted the metallic lower band to be exposed and, since the lower band is in direct contact with the barrel, it attained substantially the same temperature as the barrel. As a result the arrangement was not only a menace to the operator, who might inadvertently grasp the rifle in the vicinity of the lower band and receive a severe burn, but in addition considerable charring of the handguard wood occurred in those portions contacting the lower band. This factor is particularly detrimental when it is attempted to utilize a plastic hand-

guard, failure of the plastic generally occurring at this point of localized heating.

It is therefore an object of this invention to provide a handguard assembly for a firearm wherein no metal surface is exposed intermediate its ends, yet metallic anchoring of the fore-end of the stock is attained. Another object of this invention is to provide a one-piece handguard of substantially uniform thickness so arranged as

10 to substantially reduce the charring of the handguard caused by elevated temperatures of the metallic anchoring means.

A further object is the production of a handguard particularly adaptable to use of plastic materials.

15 It is a particular object of this invention to provide a one-piece handguard having no metallic surface exposed intermediate its ends and arranged on the barrel so as to permit slight relative longitudinal movement of the handguard with respect to the barrel to thereby prevent warping or straining of the barrel by the handguard.

The specific nature of the invention as well 25 as other objects and advantages thereof will clearly appear from a description of a preferred embodiment as shown in the accompanying drawing in which:

Fig. 1 represents an outline drawing of the 30 improved handguard assembled on a firearm similar to the U. S. rifle, caliber .30, M1.

Fig. 2 is another view, partly in section, of the 35 improved handguard in assembled relation as in Fig. 1; the handguard and cooperating members being shown in section.

Fig. 3 is a bottom view of the handguard elements assemblage independent of the firearm.

Fig. 4 is a sectional view taken along the plane 4—4 of Fig. 1.

Fig. 5 is a sectional view taken along the plane 5—5 of Fig. 1.

Fig. 6 is a sectional view taken along the plane 6—6 of Fig. 1.

Fig. 7 is a frontal view of the modified lower 45 band utilized in the practice of this invention.

In Fig. 1 the handguard 1 is shown in assembled relation on a firearm having a barrel 2, a stock 3, and a receiver 4. The rear portion of the handguard 1, i. e. the portion to the rear of the fore-end of the stock 3, is roughly semi-circular in cross-section and surrounds the upper half portion of the barrel 2. The front portion of the handguard also has the same semi-circular cross-section surrounding the barrel but in addition has 50 two tangential extensions 1a and 1b which project

below the barrel to surround the operating rod 5 of the firearm. A metallic U-shaped spacer 6 is inserted in the opening defined by the extensions 1a and 1b and lies between the barrel 2 and the operating rod 5. This spacer is inserted in and secured by longitudinal notches 1c and 1d provided respectively in handguard extensions 1a and 1b and thus serves to brace the extensions 1a and 1b.

The handguard is secured to the barrel 2 at its front end in the usual manner by the metallic front handguard ferrule 7. This ferrule engages the front end of the handguard 1 in dovetailed relation and fits loosely around the barrel 2. Thus longitudinal movement of the handguard with respect to the barrel is possible. The rear end of the handguard 1 is secured to the barrel by a conventional rear handguard band 8 which comprises a metallic semi-circular band tightly surrounding the handguard and having its ends 8a bent radially inward to engage longitudinal grooves 2a provided in each side of the barrel. By providing the grooves 2a of a greater length than the width of band 8, limited longitudinal movement of the handguard 1 with respect to the barrel is possible. The actual limitation on possible longitudinal motion of the handguard is provided at the rear by a shoulder 4a of the receiver 4, and at the front by the supporting ring 9a of the gas cylinder assemblage 9. The position of the supporting ring 9a is fixed with reference to the barrel by means of the rigid connection (not shown) of the gas cylinder assemblage 9 to the end of the barrel 2. The total length of the handguard 1 with the front ferrule 7 attached is preferably slightly less than the distance between the shoulder 4a and the supporting ring 9a.

At the center of the handguard 1, i. e., at the beginning of handguard extensions 1a and 1b, an interior recess 1e is provided which follows the contour of extension 1a, handguard 1 and extension 1b respectively. A metallic stock supporting member 10 seats in this recess. This ferrule comprises a circular band portion 10a which surrounds the barrel 2 and two depending extensions 10b and 10c which define a circular opening 10d.

The size of the opening 10d is such as to readily clear the operating rod 5 which is encompassed by the extensions 10b and 10c. The stock supporting member 10 is fixed on the barrel by a transverse pin 11 which passes through the member 10 and engages a transverse groove 2b in the barrel 2. The fore-end of the stock 3 is dovetailed into a conventional metallic stock ferrule 12 which completely surrounds the fore-end of the stock. This ferrule 12 is provided with a hollow cylindrical forward extension 12a, which loosely surrounds the operating rod 5 but is snugly engaged and secured in the opening 10d defined by the extensions 10b and 10c of the stock supporting member 10. A sling swivel 13 may be attached to the bottom portion of the stock ferrule 12.

It can readily be seen that the stock supporting member 10 limits the rearward longitudinal motion of the handguard 1 through its engagement with the base of recess 1e. Since the position of the member 10 must necessarily be fixed relative to the fore-end of stock 3, the length of recess 1e should preferably be sufficient to permit slight longitudinal movement of the handguard 1 relative to the barrel 2.

10 The handguard assemblage described thus has no hot metal surfaces exposed intermediate its ends. The thickness of the wood making up the handguard is substantially uniform throughout, thereby reducing the possibility of localized charring and/or breakage. Furthermore, the fore-end of the stock 3 is metallically anchored to the barrel 2 by the cooperation of the stock supporting member 10 and the stock ferrule 12. If plastic materials are utilized for the handguard, it 20 can be produced by one molding operation.

Since the construction described permits limited longitudinal movement of the handguard with respect to the barrel, the possibility of warping of the barrel by causes connected with the 25 handguard is eliminated. Thus the heat expansion of the barrel produces no warping effect since the barrel is free of the handguard for longitudinal movement of the extent thereby produced. Likewise a slightly oversize gas cylinder 30 cannot produce strains in the barrel upon assemblage since the handguard's possible longitudinal movement takes up such excess dimension.

I claim:

35 In a firearm having a shoulder at the junction of the barrel with the receiver, a gas cylinder member fixed to the barrel near the muzzle end, and a stock terminating between said shoulder and said gas cylinder member, the improvement comprising a ferrule slidably mounted on the barrel behind said gas cylinder member, a one piece non-metallic handguard arranged to be mounted between said ferrule and said shoulder, 40 said handguard being shaped to surround the top surface of said barrel throughout its length and having a pair of integral, spaced extensions projecting below that portion of the barrel intermediate the stock and the gas cylinder member, the length of said handguard being slightly less than the distance between said shoulder and the extreme forward position of said ferrule, means 45 for securing the front end of the handguard to said ferrule and means for securing the rear end of said handguard to the barrel, said last-mentioned means permitting limited longitudinal movement of the handguard with respect to the barrel, a metallic band member surrounding said barrel and constructed and arranged to support the forward end of said stock, said handguard having an interior recess therein to accommodate said band member, thereby providing a continuous non-metallic surface between the front and rear end portions of said handguard.

50

PETER JEROME DIFFLEY.
